UNITED STATES PATENT OFFICE.

LEO G. STEPZINSKI, OF PEORIA, ILLINOIS.

KEY-CONTROLLED SWITCH.

1,289,298.

Specification of Letters Patent. Patented Dec. 31, 1918.

Application filed July 24, 1915. Serial No. 41,778.

To all whom it may concern:

Be it known that I, LEO G. STEPZINSKI, a citizen of the United States, residing at Peoria, in the county of Peoria and State of Illinois, have invented certain new and useful Improvements in Key-Controlled Switches; and I do hereby declare that the following is a full, clear, and exact description of the invention, which will enable others skilled 10 in the art to which it appertains to make and use the same.

This invention relates to a switch for controlling ignition systems, particularly in automobiles. It pertains more particularly 15 to a switch protected by means of a lock and key, whereby said switch cannot be removed or molested in any way.

The invention includes a switch controlled by a lock and key and means operated there- 20 by to overlie and protect the screws or other means by which the switch parts are secured to the machine, while the switch is in the off or locked position, all of which will be clearly understood in the following specifica- 25 tion aided by the accompanying drawing.

In order to provide against the approp- priation of automobiles and to prevent thiev- 30 ery, it has become the custom to provide a switch that can be kept under lock and key 35 and which in consequence cannot be operated except by a person in possession of the proper key.

Sometimes these switches or parts of them are secured to the "dash" or some other part 35 of the machine by means of screws, bolts, or the like, which if left exposed can be easily withdrawn and the switch exposed so as to be operated whereby the engine can be started, making the lock and key of little value 40 in the way of protection.

It is my purpose in view of the above to provide a peculiar arrangement of parts whereby the screws, bolts or other fastening devices used to hold the switch parts in 45 place can be wholly covered from view and protected in such a way that a tool cannot be used to remove the switch while the device is locked, said fastening devices, however, being very readily removed for inspection or 50 repairs at any time it is unlocked.

In the drawing forming a part of this ap- 55 plication,

Figure 1 shows the working parts of the switch.

Fig. 2 shows the front side of an outer 55 closure for said switch.

Fig. 3 shows the back side of the closure and certain working parts; and,

Fig. 4 shows a side elevation, in part sec- 60 tion, of the switch body and the said closure. Fig. 5 is an enlarged section of a portion of the switch body showing a threaded plug.

The switch body, Fig. 1, consists of a back portion A and a raised marginal wall B cre- 65 ating a recess within which are the working parts of the switch of which C is a rotatable member suitably mounted in the back A. Affixed to said member is a metal plate in- 70 cluding an arm D acting to limit the move- ment of the switch, and including also a part E in permanent sliding engagement with a conductor F secured on said back A.

G H are spring conductors secured in the back A one of which is connected with the magneto, for example, and the other with 75 the batteries of the machine. These con- ductors lie in the path of the part E and the latter serves to form a connection with either of them and said conductor F, which latter is connected to some part of the machine not 80 necessary to describe and which is common practice.

The rotatable member C is slotted at J across its center of rotation and said slot lies 85 parallel to the arm D by preference.

The portion to which I now wish to direct particular attention and forming the subject of my invention is shown in Figs. 2, 3 and 4, a part of the same, however, being shown in Fig. 1. It consists of a body similar to that 90 shown in Fig. 1 and already described in that it has an outer wall K which forms a closure for the switch body shown in Fig. 1, and includes a raised margined wall L shown in cross-section in Fig. 4.

This body K L overlies the body A B, see Fig. 4, the two parts being secured to the "dash" M or some other portion of the ma- 95 chine by means of suitable fastening devices.

In the present instance I have shown 100 screws N as the fastening means it being ob- served that these pass through holes O in the portion K and through holes P in the switch body in Fig. 1, and thence into the "dash". These may be so called "wood- 105 screws" or they may be machine screws or bolts, so long as the part which can be turned by a tool is hidden and protected by the means to be described.

On the outer face of the wall K is any 110 usual extended boss Q to receive any suitable lock structure R, Fig. 2, having a barrel S

turned by means of a key and extended through the wall into the recess at the back created by the wall L. To the inner end of the barrel, see Fig. 3, is secured by means of 5 screws T, for example, a metal plate S' which includes two divergent arms U so disposed as to overlie two of the screws N. Extending from the plate also is an arm V provided near its extremity with a pin W.

10 2 is a rock arm pivoted at 3 on the wall K, one of its portions at one side of the pivot having a slot 4 to receive the said pin W, its extremity at the other side of the pivot adapted to overlie the lower screw hole as 5 shown. The described plate S' is provided with an extended key portion 5 adapted to engage the slot J of the described rotatable member C.

The holes O in the wall L, Figs. 1 and 2, 0 are each of two different diameters, as clearly shown in Fig. 4, one being just large enough to receive the shaft or shank of the screw, and countersunk to receive the screw head, the outer portion of the hole being 25 large enough to permit the head to readily pass through.

The wall L through which the screw holes extend is provided with extended portions or ears 6 and these, as indicated in Fig. 4, 30 are slotted at 7 in the same plane with the arms U and member 2.

It is to be observed that when the barrel S of the lock is turned, the divergent arms U are swung on the same center and will enter 5 or leave the said slots 7.

The same is also true of the member 2 which is swung on its pivot by means of the arm V. The dotted lines, in Fig. 3 clearly illustrate the action and the position the 40 parts take when the key is turned in the lock in either direction to throw the switch to either extreme.

As a matter of fact, the dotted lines in Fig. 3 referred to take the position shown 45 when the switch is thrown to the position shown in broken lines in Fig. 1, it being remembered that the switch body is seen from the front in Fig. 1, while the back of the body K L is seen in Fig. 3. The full lines in 50 the figure last referred to take the position shown when the switch is thrown to the central or "off" position shown in full lines in Fig. 1.

The lock is of such a type that the key in 55 order to be withdrawn must be placed in a vertical or upright position and in taking this position the part E of the switch is removed from the contact members G H with which it may have been in contact, the circuit being left broken.

As this action takes place the divergent arms U must at the same time enter the slots 7, as also the pivoted member 2, the screw heads being thus covered from view, it being 65 impossible to introduce a tool of any kind to

reach the screw, nor can the parts U be moved to one side, since they are a rigid part of the lock.

Said parts U if made of hardened steel cannot be drilled through so that the fastening devices N cannot be reached in any way.

It is not my wish to be confined to the exact arrangement shown and described for closing the screw holes and covering the securing device since I may vary the structure 75 without departing from the spirit and intent of the invention.

For instance, I have shown and described a peculiar arrangement with regard to parts V² to provide means to protect the lower 80 screw of the switch. This is only occasioned by the fact that the screw mentioned is spaced farther from the center about which the arms U turn. If this screw were substantially the same distance from the center of 85 rotation as the others then a single rigid arm equivalent of the said arms U may be employed as stated.

Again, in Fig. 5 the outer portion of the hole O in the wall L may be closed by a 90 threaded plug 8 which at its inner end may reach as far as the head of the screw N, if desired. At any rate it is furnished with an annular groove 9 to lie in the same plane with the slot 7 and the arm U so that the end 95 of the latter can enter it as clearly shown.

This plug 8 closes the hole O at the outer surface of the wall K giving a more finished appearance than shown in Fig. 2.

The arm U may be shortened sufficiently 100 to just pass into the groove 9 and it will be understood that an attempt to remove the plug would be thwarted since the shoulder at the inner end of the plug will be brought against the arm and constitute a stop to further turning.

Again, the plug if of hardened steel cannot be touched by a drill and thus access to the interior of the device by such a method will be thwarted.

The body K L together with the parts which it carries may form a separate article of manufacture to be sold separately and attached to the body A. That is to say, where a switch is already in use the body K L may 115 be adapted in form to fit it and include the screw holes O in the proper position to register with those of the switch, the arms U and the part 2 being properly disposed so as to cover them.

Having thus described my invention, I claim:

1. The combination of a base and a casing overlying the same, a lock mounted in said casing including an oscillating locking part 125 and an extension thereof, there being a notch in the wall of the casing in position to receive the extension in the movement of the locking part, there also being an aperture piercing that part of the wall having 130

- the notch, a member lying in the aperture to secure the casing to the base, its end lying below the notch, and a member lying in the aperture outward from the notch to cover 5 the first named member and having a notch therein corresponding with that of the casing in position to receive the said extension.
2. The combination of a base and a casing, a lock mounted in said casing including an 10 oscillating part and a lateral extension thereof, there being a bifurcated extension on the casing lying in the same plane as the first named extension, the latter adapted to enter between the bifurcations, there being 15 an aperture extending through said bifurcated extension, a member engaging that part of the latter lying nearest the base and engaging the latter for securing the casing and base together, the member being normally covered by the said first named extension, and a member inserted in the aperture of the other parts of the bifurcated extension and engaged by the first named extension. 25
3. The combination of a casing and a base, a lock in said casing including a barrel and a part extending from it, said casing having a notch in its wall adapted to receive into it the said part in the movement of the barrel, 30 there being a hole through said casing cutting through said notch, a screw lying in said hole at one side of said notch securing

the casing to said base, and a plug having threaded engagement with the other portion of the hole at the opposite side of the notch 35 and terminating at one of its ends at the screw and at its other end outward from the notch and provided with an annular groove in the same plane with said notch and adapted to receive the said part on the 40 said barrel.

4. The combination of a casing and a base, a lock mounted in said casing including a rotating barrel portion and a part extending from it, there being a notch in the wall of 45 the casing in position to receive into it the said part, there being a hole through said casing cutting the notch at right angles, a screw seated in the hole at one side of the notch adapted to secure the casing to the 50 said base, and a plug having threaded engagement with the other portion of the hole at the opposite side of the notch, the same having an annular groove substantially in the same plane with the notch adapted to receive into it the said part of the said barrel 55 and adapted to prevent the removal of said plug.

In testimony whereof I affix my signature, in presence of two witnesses.

LEO G. STEPZINSKI.
